UNITED STATES PATENT OFFICE.

JOSEPH H. HEBERT, OF COLUMBUS, OHIO.

DESIGN FOR A CLEANING-TOOL.

59,348.

Specification for Design.

Patented Oct. 11, 1921.

Application filed June 7, 1921. Serial No. 475,727. Term of patent 7 years.

To all whom it may concern:

Be it known that I, JOSEPH H. HEBERT, a citizen of the United States, residing at Columbus, in the county of Franklin and State of Ohio, have invented a new, original, and ornamental Design for a Cleaning-Tool, of which the following is a specification, reference being had to the accompanying drawing, forming part thereof.

Figure 1 is a plan view of a cleaning tool, showing my new design, and

Fig. 2 is a side elevation of the tool.

I claim:

The ornamental design for a cleaning tool, as shown.

JOSEPH H. HEBERT.

Witnesses:

M. A. STEPHENS,
W. S. McDOWELL.
